W. G. WALL

OIL RECTIFIER

Filed Sept. 26, 1925

UNITED STATES PATENT OFFICE.

WILLIAM G. WALL, OF INDIANAPOLIS, INDIANA, ASSIGNOR TO RECTIFIER MANUFACTURING COMPANY, OF INDIANAPOLIS, INDIANA, A CORPORATION OF INDIANA.

OIL RECTIFIER.

Application filed September 26, 1925. Serial No. 58,950.

My said invention relates to oil rectifiers and it is an object thereof to provide in conjunction with the rectifier an improved construction of this character with a strainer 5 for straining particles of foreign matter out of the oil which strainer shall be highly effective and capable of use over an extended period of time without becoming clogged.

Referring to the accompanying drawings 10 which are made a part hereof and on which similar reference characters indicate similar parts,

The single figure is a side elevation of my device in position on an automobile.

15 In the drawings reference character 10 indicates the carburetor of an internal combustion engine which may be a part of an automobile, my device being intended primarily for use in automobiles though it is 20 not necessarily limited to such use. A pipe 11 is connected to the carburetor at the air intake side of the throttle valve 12 said pipe being centrally connected at its other end to the top of a casing 13 having a distillation 25 chamber surrounded by a jacket 14 to which exhaust gases are admitted from the exhaust side of the engine by way of passages indicated at 15. The upper part of the chamber constitutes a distillation chamber in 30 which diluted oil is heated so as to vaporize volatile constituents as gasoline and water which are then drawn off through the pipe 11 by means of suction from the carburetor. In previous constructions it has been 35 customary to attach the outlet pipe from the rectifier to the intake manifold but this is objectionable for the reason that the suction through said pipe decreases in accordance with increasing speeds of the engine 40 and vice versa. This is exactly the opposite of the result desired since the greater the speed of the engine the more rapidly the oil circulates and a greater suction is required to eliminate the impurities. The 45 heat in the exhaust of course increases with increasing speed of the engine at the same time that the flow of oil decreases in such earlier constructions and thus there is danger of too much distillation at high 50 speeds and too little distillation at low speeds. The greater the speed of the engine therefore the more rapid should be the passage of the oil through the rectifier.

Another objection to former practice is that when idling such connections as above referred to break the vacuum in the intake manifold and cause sensitive engines to miss which is objectionable.

55 A pipe 16 is located centrally of the casting 13 said pipe being open at its upper end 60 which is normally closed by a valve 17 seating in the upper end of the pipe 16. This valve is opened and closed by means of a float 19 and when opened admits air to the upper end of the chamber, the air in this 65 instance being taken from the crank case though the pipe may open directly to the outer air if desired. A siphon 20 provides means for drawing off the purified oil from the distillation chamber when a sufficient 70 amount has accumulated therein, this siphon leading back to the crankcase or to a suitable reservoir for pure oil. It will be seen that opening of the valve 17 relieves the 75 partial vacuum in the upper part of the distillation chamber and thus enables the oil to escape with greater rapidity. If desired the parts may be so proportioned that the upper end of valve 17 closes the adjacent end 80 of pipe 11 so as to break the suction more effectively by interrupting the communication to the carburetor.

85 Diluted oil is supplied to a chamber at 21, which chamber in this instance is below the distillation chamber, by means of a high pressure line 22 to which oil is supplied by a pump or other suitable means. From the high pressure line the oil passes through a pipe 23 to the chamber 21, and if desired a 90 by-pass 24 may be provided at an intermediate point to reduce the pressure by carrying off an excess of oil and prevent too great a supply to the distillation chamber.

95 The chamber 21 is located below the distillation chamber partly for the reason that the sediment in the oil is thus given a chance to sink to the lower part of the chamber where it can be drawn off through a port normally closed by a screw-plug 25. In the present construction the part of the casing which includes the chamber 21 is separable from the main casing being connected thereto by screws 26. A port at the upper end of the chamber 21 is surrounded by an annular flange 27 having an outwardly projecting 100 lip.

Between the sediment chamber and the distillation chamber there is an intermediate chamber 28 in which a fabric strainer 29 is arranged for separating the solid impurities from the oil. At its lower end the strainer is held in place about the lip on the flange 27 by means of a spring ring or wire 29. A removable partition 30 is placed at the upper end of the intermediate chamber adjacent the bottom of the distillation chamber and is so held by a spring 33 or in any other convenient way, and this partition is provided with one or more openings or ports 31 therethrough.

15 I make the strainer 29 from a substantially cylindrical fabric bag preferably of non-inflammable fabric, as for example asbestos, in order to provide a large area through which the lubricant may pass.

20 Rings 34 and 35 are alternately placed inside and outside of the bag to cause the same to fold over in Japanese lantern fashion and when collapsed occupy a relatively small space within the chamber.

25 It will be obvious to those skilled in the art that various changes may be made in my device without departing from the spirit of the invention and therefore I do not limit myself to what is shown in the drawings and described in the specification but only as indicated in the appended claims.

Having thus fully described my said invention, what I claim as new and desire to secure by Letters Patent, is:

35 1. An oil rectifier comprising a casing, a sediment chamber at the bottom of the casing, a partition between the sediment chamber and the upper part of the casing, an oil inlet into said casing, an oil outlet 40 from said casing, and a strainer between said inlet and outlet comprising a bag and having means for holding the same collapsed, substantially as set forth.

2. An oil rectifier comprising a casing, a sediment chamber at the bottom of the casing, a removable partition between the sediment chamber and the upper part of the casing, an oil inlet into said casing, an oil outlet from said casing, a strainer between 50 said inlet and outlet comprising a bag and having means for holding the same collapsed, and a spring for maintaining said bag and partition in position, substantially as set forth.

55 3. An oil rectifier comprising a fluid chamber, a sediment chamber below said fluid chamber, a strainer between said sediment and fluid chambers comprising a bag, and rings placed alternately inside and outside 60 of said bag to hold the same axially collapsed, substantially as set forth.

4. An oil rectifier comprising a fluid chamber, a sediment chamber below said fluid chamber, a removable partition be- 65 tween said fluid and sediment chambers, a

strainer below said partition comprising a bag the end of said bag being disposed against the partition, and spring means holding said bag and partition in position, substantially as set forth. 76

5. An oil rectifier comprising a casing having upper and lower chambers, a removable partition between said chambers, openings through said partition, an inlet for oil into the lower chamber, an outlet for oil 75 from the upper chamber, a strainer located below said partition having a plurality of folds extending transversely of the chambers through which the lubricant flows from the lower to the upper chamber for separating solid particles therefrom, substantially as set forth. 80

6. An oil rectifier comprising a fluid chamber, a sediment chamber below the fluid chamber, an air pipe extending 85 through said sediment chamber and terminating in the fluid chamber for admitting air thereinto, an inlet for oil into the sediment chamber, an outlet for oil from the fluid chamber, a strainer disposed between the sediment and fluid chambers said strainer having a plurality of folds extending transversely of the chamber, substantially as set forth. 90

7. An oil rectifier comprising a fluid chamber and a sediment chamber, an inlet for oil into the sediment chamber, a siphon for removing the oil from the fluid chamber, means connected with the carbureter for creating a suction in the fluid chamber, and a strainer located between the sediment and fluid chambers said strainer having a plurality of folds extending transversely of the chamber, substantially as set forth. 95 100

8. An oil rectifier comprising a fluid chamber and a removable sediment chamber, an inlet for oil into the sediment chamber, a siphon for removing the oil from the fluid chamber, means connected with the carbureter for creating a suction in the fluid chamber, and a strainer located between the sediment and fluid chambers said strainer comprising a bag having rings alternately placed inside and outside of the same to hold the strainer collapsed, the said strainer being removable with the sediment chamber, substantially as set forth. 110 115

9. The combination in a rectifier of an elongated casing having its interior formed of two diameters with a shoulder between the same, a strainer in said casing, a removable closure for the end of the casing adjacent the larger diameter, a body supported by said removable closure and extending longitudinally of said casing, a partition slidably mounted upon said body and adapted to seat against said shoulder, means between the partition and the removable closure for normally yieldably forcing said 120 125 130

perforated partition against the shoulder when the parts are assembled, substantially as set forth.

10. The combination in a rectifier of an elongated casing having its interior formed of two diameters with a shoulder between the same, a removable closure for the end of the casing adjacent the larger diameter, a body supported in said removable closure and extending longitudinally of said casing, a perforated partition slidably mounted upon said body and adapted to seat against said shoulder when the parts are assembled, a spring about said body between the partition and the removable closure for normally forcing said partition against the shoulder, said closure having an upstanding rim and a strainer fastened about said rim and closely engaging said body beneath said partition, substantially as set forth.

11. The combination in an oil rectifier of an elongated casing having spaced inlet and discharge openings therein, a strainer in said casing, a removable closure for one end of the casing, a shoulder formed in said casing between said spaced openings, body mounted in said removable closure and extending into the casing beyond said shoulder, a partition supported on said body and adapted to bear against said shoulder, spring means associated with said body carried by the closure

between said partition and said closure for normally forcing said partition against said shoulder, substantially as set forth.

12. The combination in an oil rectifier adapted to be inserted in the pressure line of the lubricating system of an engine, of a fluid chamber having an oil discharge passage and a removable sediment chamber having an inlet passage, an air pipe having an open upper end mounted in said removable sediment chamber and extending into said fluid chamber, a partition loosely supported about said air pipe removable with said sediment chamber, a shoulder formed on the body of the device between the sediment chamber and the fluid chamber, means associated with said air pipe for yieldingly pressing said partition against said shoulder, a float supported in said fluid chamber on said air pipe and having means for closing the open upper end of the air pipe, an inlet for oil into the sediment chamber, and a strainer in said sediment chamber below said partition whereby the oil will be caused to pass therethrough in its path through the device, substantially as set forth.

In witness whereof, I have hereunto set my hand at Washington, District of Columbia, this twenty-fifth day of September, 1919. A. D. nineteen hundred and twenty-five.

WILLIAM G. WALL.
